CLAIM

The ornamental design for a pill dispenser, as shown and described.

DESCRIPTION

FIG. 1 is a top perspective view of a pill dispenser showing an open configuration of our new design;

FIG. 2 is a bottom perspective view of the design of FIG. 1;

FIG. 3 is front elevation view of the design of FIG. 1;

FIG. 4 is a back elevation view of the design of FIG. 1;

FIG. 5 is a left side view of the design of FIG. 1;

FIG. 6 is a right side view of the design of FIG. 1;

FIG. 7 is a top plan view of the design of FIG. 1; and

FIG. 8 is a bottom plan view of the design of FIG. 1;

FIG. 9 is a top perspective view of a pill dispenser showing a closed configuration of our new design;

FIG. 10 is a bottom perspective view of the design of FIG. 9;

FIG. 11 is front elevation view of the design of FIG. 9;

FIG. 12 is a back elevation view of the design of FIG. 9;

FIG. 13 is a left side view of the design of FIG. 9;

FIG. 14 is a right side view of the design of FIG. 9;

FIG. 15 is a top plan view of the design of FIG. 9; and,

FIG. 16 is a bottom plan view of the design of FIG. 9.

The broken lines in the drawings depict portions of the pill dispenser that form no part of the claim.
